MACHINE SUPPORTING ASSEMBLY FOR
BUSINESS MACHINESWilliam H. von Hacht, Bronxville, N. Y., assignor
to Underwood Corporation, a corporation of
Delaware

Application November 16, 1944, Serial No. 563,729

8 Claims. (Cl. 45—6)

1

This invention relates to mountings for supporting typewriters, adding machines, accounting machines and other business machines, while the machines are in operation.

The primary objects of the present invention are to improve the construction and mode of operation of the mountings for business machines, particularly with a view of increasing the convenience and comfort of the operator in operating such machines and to produce a mounting construction which enables the operator to perform the required operations more easily and efficiently and with less body strain and tiring effect as compared with prior constructions.

Another object of the invention is to provide a novel and improved construction for supporting business machines in which the machine and the sheets from which postings are taken may be positioned more conveniently for the operator respectively to operate and inspect during posting operations and a readily accessible repository is provided for the printed sheets.

Another object of the invention is to produce a novel construction for supporting business machines in which the machine may be adjusted vertically at a plurality of points to locate the same accurately in the proper position for operation.

Still another object of the invention is to produce a mounting for business machines comprising units or sections in which the units are secured together so as effectively to prevent undue vibrations from being set up by the operation of the machine.

With the above and other objects in view the invention consists in a mounting embodying the novel and improved features, constructions and combinations of parts hereinafter described and particularly pointed out in the claims, the advantages of which will be readily understood and appreciated by those skilled in the art.

The various features of the invention will be clearly understood from the accompanying drawings illustrating a construction embodying the invention in its preferred form and the following detailed description of the construction therein shown.

In the drawings:

Figure 1 is a perspective view illustrating a mounting structure embodying the invention.

Figure 2 is a view in vertical section of the structure taken substantially on the lines 2—2 of Figure 1 and showing the closure 131 raised slightly above its normal closed position and the slide 141 in a forward position.

2

Figure 3 is a detail perspective view illustrating one of the parts of the construction shown in Figure 2.

Figure 4 is an underside plan view of the mounting structure illustrated in Figure 1.

Figure 5 is a perspective view illustrating certain of the parts of the structure shown in Figure 1 with the posting shelf in a different position and a device resting on said shelf for holding ledger or other sheets from which postings are to be taken.

Figure 6 is a detail view in rear elevation illustrating the construction for adjustably suspending the platform for supporting the business machine.

Figure 7 is a detail view in vertical section taken substantially in a plane containing the fore-and-aft center line of the platform and also illustrating the mechanism for suspending the platform.

Figure 8 is a detail perspective view illustrating the posting shelf and certain devices for locating and supporting the posting shelf in different vertical positions looking from the underside of the shelf.

Figure 9 is a detail perspective view illustrating, on an enlarged scale, certain of the devices shown in Figure 8 for locating and supporting the posting shelf, looking from the underside of the same.

Figure 10 is a detail view in elevation illustrating the devices shown in Figure 9 with certain parts in different relative positions.

Figure 11 is a detail sectional view taken substantially on the line 11—11 of Figure 10, and

Figure 12 is a detail view illustrating the upper part of the right hand cabinet with a portion of the top wall in open position.

The mounting illustrated in the drawings of this case comprises a right-hand unit indicated at 1, a left-hand unit indicated at 3 and a table or platform 5 (see Figs. 4, 6 and 7) supported between said units for holding a business machine 7. The unit 1 consists of a cabinet having the general form of a rectangular parallelepiped. This unit is formed with fixed side walls 9 and 11, a fixed rear wall 13 (see Fig. 4), a fixed bottom wall 15 and a top wall 17, a portion 17a of which is fixed to the left side and rear walls. The unit is also provided with fixed front walls 19 and 21 arranged with relation to each other to form a re-entrant angle. These front walls extend from the top wall part way to the bottom wall. The above walls of the unit are secured to each other and arranged to form a hollow boxlike structure

having the space within the same arranged for storage of supplies. The unit is provided with legs 22 upon which it rests.

The mounting unit 3 consists of a cabinet also having the general form of a rectangular parallelepiped and provided with fixed side walls 33 and 35, a fixed rear wall 37, a fixed bottom wall 38 and a fixed top wall 39. These walls are all constructed and arranged and secured together to form a hollow boxlike structure having the space within the same adapted for the storage of supplies. This unit is provided with legs 40 to support the same.

The two units 1 and 3 are rigidly fastened together in spaced relation to support a business machine between the same. The bases of the units are secured together by a relatively long narrow plate or board 41. This board is rigidly fixed to the unit 3 as by means of a series of bolts 43, Fig. 4, passing through the bottom wall 38 of the unit and through said board. The right-hand end of the board is rigidly fixed to the unit 1 by means of an angle bracket 45, to one arm of which the board is attached by means of a bolt 47. The other arm of the bracket is secured to the side wall 11 of the unit by means of bolts 49.

The shelf or platform 5 for supporting a business machine, in the illustrated construction, comprises, a body portion 5a, and a forward portion 5b preferably made of sheet metal and bent in cross section into the form shown in Fig. 7. The rear margin of the forward portion 5b is attached to the overlapping forward margin of the body portion 5a by bolts 5c, the two portions of the platform being spaced by spacing blocks 5d through which the bolts pass. The body portion 5a is cut away at 5e to provide for the passage of a treadle rod or other element extending downwardly from the business machine.

The platform 5 is suspended upon the overhanging inner portions of the fixed top walls of the two units or cabinets 1 and 3. The suspending means is arranged so that the four corners of the platform may be adjusted vertically to adjust correspondingly the business machine supported on the same. In the present construction, the left-hand forward corner and the left-hand rear corner of the platform, respectively, are suspended upon bolts 51 passing through the inner marginal portion of the fixed top wall 39 of the unit 3, which overhangs or extends beyond the side wall 33, and through the platform, these bolts having nuts 53, Fig. 7, threaded thereon to engage the underside of the platform. The right-hand forward corner and the right-hand rear corner of the platform 5 are respectively suspended upon bolts 55 passing through the inner marginal portion of the fixed section 17a of the top wall of the unit 1, which extends beyond or overhangs the inner side wall 11 of said unit, and through the platform, the bolts 55 having nuts 57 threaded thereon to engage the underside of the platform.

The legs 22 of the unit 1 and the legs 40 of the unit 3 may each be adjusted toward and from the corresponding unit to adjust the heights of the respective corners of the units supported by the several legs. Each of the legs is mounted on a bolt or screw 59 passing through the bottom wall of the unit and secured to said wall by a nut 59. The lower end portion of the screw is threaded into the leg and is held in adjusted position thereon by a lock nut 61, a lock washer 63 being interposed between the nut and the leg.

By adjusting the legs with relation to each unit, a four point adjustment of the unit may be obtained.

The adjustable connections between the legs 22 and the unit 1 and between the legs 40 and the unit 3 enable each corner of each unit to be adjusted vertically. Thus each unit may be adjusted vertically as a whole, and each side and each corner of the unit may be raised and lowered as desired. The platform 5 which supports the machine also may be correspondingly adjusted. Thus the platform may be adjusted vertically as a whole and the front and rear, the two sides and each corner may be raised or lowered. The provisions for adjustment of the legs of each unit, in connection with the provision for adjustment of the corners of the platform, enables a very extensive adjustment of the machine to be obtained, both vertically to suit the operator, and angularly to locate the machine accurately in a level position. The locating of a business machine in a level position is often so important that a spirit level is often used in positioning the mounting and the machine. The irregularities and unevenness of the floors of the buildings in which the machines are placed, in many cases, make this a difficult problem. The importance of all these provisions for the vertical adjustment of the mounting and the machine will therefore be appreciated.

The unit 1 is provided with a posting shelf 65 supported in the re-entrant angle between the two front walls 19 and 21.

The posting shelf 65 preferably is rectangular in outline and extends from the re-entrant portion of the unit 1 diagonally to the left partially across the front of the top wall 17a of the unit. The posting shelf also extends forwardly some distance beyond the unit 1 as shown in Figs. 1, 4, and 5.

The posting shelf may be used in the position shown in Fig. 1 but in posting operations the shelf is usually adjusted to a position below the top wall of the unit 1 as shown in Fig. 5, this position being determined to suit the comfort and convenience of the operator.

Figure 5 shows a rack 101 for supporting ledger sheets or other sheets containing material to be posted resting on the posting shelf. This rack comprises a base plate 103 and inclined side plates 105 attached at their lower ends to said base plate. The posting shelf is attached to the unit so that it may be located in an uppermost position with its upper surface substantially in the plane of the upper surface of the top wall 17 as shown in Fig. 1 or in any one of a number of different positions below this uppermost position to suit the convenience of the operator and the character of the work being done. Fig. 5 shows the shelf in one of the latter positions. To enable the posting shelf to be quickly and easily located and secured to the unit in different vertical positions, two parallel spaced mounting bars 67 are attached to the front wall 21 of the unit 1 in substantially vertical positions and each bar is formed with a series of vertically spaced holes 69 arranged to receive pins 71 projecting from one of the rear edges of the posting shelf. These holes preferably are uniformly spaced vertically and are arranged in the two bars in pairs, the holes of which are at the same height or distance from the top wall 17. A third mounting bar 73 is attached to the forward wall 19 of the unit in substantially a vertical position and is formed with a series of openings 75 spaced to correspond

with the openings 69 to receive the projection 77, on a holding plate 79 attached to the underside of the posting shelf. The projection 77 is formed with a transverse slot 81 thereby producing a relatively narrow neck 83 and an end portion 85 having substantially the same width as the body of the projection 77, said slot being arranged to receive a portion of mounting bar 73. The openings 75 each comprise a lower portion slightly wider than the projection 77 and a relatively narrow recess 87 to receive the neck 83 of said projections.

With this construction, in attaching the posting shelf to the unit 1, the shelf is first manipulated to engage the pins 71 in the openings 69 of substantially the same height in the mounting bars 67. The shelf is then further manipulated to engage the projection 77 on the holding plate 79 in the lower portion of a corresponding opening 75 in mounting bar 73. The movement of the shelf in a direction to insert the projection 77 in the opening 75 is limited by the engagement of the stop face 89 on the holding plate 79 with the bar 73. The slot 81 is located on the projection 77 so that, when the movement of the shelf is thus limited, the slot 81 is placed in registration with the mounting bar 73. With the parts thus positioned, the portion of the shelf, to which the holding plate 79 is attached, is lifted to engage the neck 83 in the recess 87 in the opening as shown in Fig. 11, and to engage the portion 88 of the mounting bar 73 in the slot 81. A locking bolt then operates to lock the parts in these relative positions.

This locking bolt is indicated at 91 and consists of a plate-like member mounted to slide on the under side of the plate 79 by means of headed studs 93 secured in the plate and engaging in slots 95 in the bolt. The bolt is acted upon by a coil spring 97 which tends constantly to move the same to its outer or locking position. The bolt may be withdrawn by means of a down-turned finger piece or handle 99 formed on the inner end of the bolt. The outer end of the bolt has substantially the same width as that of the projection 77 so as to fit in the lower portion of the opening 75. When the posting shelf is manipulated to engage the projection 77 in the lower portion of the opening 75, the locking bolt 91 is pushed back by its engagement with the bar 73. When the portion of the posting shelf, to which the plate 79 is attached, is lifted to engage the neck 77 in the recess 87, the bolt 91 snaps outward into the wider portion of the opening 75 under the influence of the spring 97 to lock the shelf in position.

The re-entrant portion of the unit 1 extends only part way down from the top to the base of the unit. The unit is provided with a horizontal partition 107, extending from the front to the back of the unit between the top and bottom wall, and dividing the same into upper and lower compartments, the lowermost position of the posting shelf being just above this partition. Access to the upper compartment is provided for by mounting the portion 109 of the top wall to swing upon hinges 109, Fig. 4, to a position above the unit.

The side walls 9 and 11 of the unit 1 are provided, below the partition 107, with a series of grooves 111 in which are mounted forwardly and rearwardly movable slides 113 forming shelves to be used for the storage of supplies. The front of the lower compartment is closed by means of closure 115 suspended on a forwardly and rear-

wardly movable slide 117 also mounted in grooves in the side walls of the unit 1 and located below the partition. This closure is arranged to engage between the side walls 9 and 11 and above the bottom wall 15 when the slide 117 is moved to its innermost position.

The unit 3 is provided with a partition 119 dividing the same into upper and lower compartments and a forwardly and rearwardly slideable drawer 121 is arranged in the upper compartment. The drawer is divided by across partition 123 into forward and rear chambers 125 and 127. The forward chamber 125 is particularly intended to receive bills after they are printed on the business machine. To enable the bills to be dropped into the chamber 125 when the drawer is closed, the top wall 39 of the unit is formed with an opening 129. A removable closure 131 is provided for this opening and, when inserted, rests upon plates 133 attached to the under side of the top wall 39 and each extending diagonally across a corner of the opening.

The portions of the side walls 33 and 35 of the unit 3 below the partition 119 are formed with parallel spaced grooves 135 and shelves 137 arranged to slide forwardly and rearwardly in these grooves are provided to receive supplies. For convenience in the application of supply sheets to the shelves, and the removal of said sheets therefrom, the shelves may be pulled out so that their forward portions occupy different forward positions with relation to the unit 3 as shown in Fig. 2.

In order to close the forward end of the lower compartment, a closure 139 is mounted on and depends from a slide 141 arranged to slide forwardly and rearwardly in grooves in the side walls 33 and 35 just below the partition 119. This closure normally depends from the slide 141 in the position shown in dotted lines in Fig. 2 and when the slide is moved rearwardly to its innermost position, with the closure in this position, the closure engages between the side walls of the unit and above the bottom wall to close the compartment.

To enable the closure 139 to be swung up out of the way when the forward end of the lower compartment is to be open, the closure is suspended from the slide 141 on hinges 143 to swing about a horizontal axis. The closure thus may be swung up against the underside of the slide as shown in Fig. 2. The closure may be held in this position by any suitable releasable latch. In the construction shown, the latch consists of a slide bar 145 having its ends down-turned to form handles and slidably mounted on the underside of the mounting or supporting plate 147 fixed to the underside of slide 141.

The parts are constructed so that the forward edge of the mounting plate 147 lies adjacent the rear edge of the closure 139 when the closure is folded up against the underside of the slide 141. The slide bar 145 is mounted on the forward margin of the plate 147 and is normally retracted rearwardly beyond the rear edge of the closure 139. The slide bar, however, is arranged to be projected laterally beyond the rear edge of the closure. The slide bar is provided with inclined slots 149 and is slidably mounted on the mounting plate 147 by means of headed studs 151 secured to the mounting plate and engaging in said slots. Thus when the slide bar is moved longitudinally on the mounting plate, it is shifted sidewise. When the slide bar is located longitudinally in one limiting position, its right-hand

edge, Fig. 2, will clear the rear edge portion of the closure 139. When the closure is folded up, with the slide bar in this position, and the slide bar is then moved longitudinally to its opposite limiting position, the right-hand edge portion (Fig. 2) of the bar will be moved across the rear edge portion of the closure to hold the closure in folded position.

The closure 115 is mounted on the slide 117 to swing on hinges (not shown) in substantially the same manner that the closure 139 is mounted on the slide 141 so that the closure 115 may be swung up out of the way against the slide 117 and the latter closure is held in this position by means of a latch bar such as the latch bar 145 shown in Fig. 3 or by any other suitable latch device.

It will be noted that the posting shelf 65 is mounted in the recess between the two angularly arranged front walls of the cabinet 1 and extends from the rear or inner portion of said recess forwardly and to the left diagonally toward the operator's position in front of the machine 1. In billing from ledger sheets, these sheets may be placed in a rack 191 resting on the shelf, the shelf being adjusted in a vertical position most convenient for the operator. The closure 131 is removed from the opening 129 so that the bills or other work sheets, after being typed, may be dropped successively through 30 the opening 129 into the compartment 125. This prevents them from being blown about or otherwise displaced.

The slides or shelves 113 and 137 respectively are removable from the grooves in the side walls 35 of the corresponding unit and may be inserted in any set of grooves in the unit. Thus the spacing of the shelves may be varied as desired.

It is to be understood that the particular structure shown in the drawings of this application is merely illustrative of the invention and that the invention is not limited thereto but that it may be embodied in other forms within the scope of the claims.

Having explained the nature and object of the invention and having specifically described a construction embodying the invention in its preferred form, what is claimed is:

1. In a machine supporting and cabinet assembly for business machines comprising a platform for supporting a business machine, means for supporting said platform at a distance from the floor upon which the assembly is placed with a space beneath the platform for the reception of the feet and legs of the operator including a structure for supporting one side of said platform, a cabinet located at the other side of said platform and devices on said cabinet for supporting the adjacent side of said platform; a shelf mounted at the front of the cabinet and extending rearwardly for a substantial distance beyond the front of said platform and extending forwardly beyond the cabinet at an oblique angle thereto toward the position of the operator and means for rigidly attaching at least two sides of said shelf to the forward portion of said cabinet in each of a plurality of vertical positions.

2. In a machine supporting and cabinet assembly for business machines comprising a shelf for supporting said shelf at a distance from the floor upon which the assembly is placed with a space beneath the shelf for the reception of the feet and legs of the operator including a structure for supporting one side of said shelf, a cabinet

located at the other side of said shelf and devices on said cabinet for supporting the latter side of said shelf; the cabinet having front walls arranged to form an angular recess, a second shelf mounted in said recess at the front of the cabinet and extending rearwardly for a substantial distance beyond the front of said first shelf and extending forwardly beyond the cabinet at an oblique angle thereto toward the position of the operator and means for rigidly attaching said latter shelf to at least two of said angularly arranged forward walls of said cabinet in each of a plurality of vertical positions.

3. In a machine supporting and cabinet assembly for business machines comprising a cabinet, a device for supporting a business machine located at one side of said cabinet, means on said cabinet for supporting the adjacent side of said device and a cooperating supporting structure for supporting the opposite side of said device; a shelf attachable to the front of said cabinet in a plurality of vertical positions, fastening means on two or more edges on said shelf, means on a corresponding number of outer walls of said cabinet and cooperable with said fastening means in each of said plurality of vertical positions for rigidly and releasably attaching said shelf to said cabinet, a compartment in the upper portion of said cabinet to the rear of said shelf and a compartment in the lower portion of said cabinet below the first compartment and below the lowermost position of said shelf.

4. In a machine supporting and cabinet assembly for business machines comprising a cabinet having a plurality of front walls, a support for a business machine, means for attaching one side of said support to one side of said cabinet, and a supporting structure for the other side of said support, a plurality of sliding horizontal shelves mounted in vertically spaced relation in a lower portion of said cabinet, a shelf above said plurality of shelves, said shelf extending forwardly and obliquely from said cabinet, and cooperating means on a plurality of sides of said shelf and a corresponding plurality of said front walls of said cabinet for rigidly attaching said shelf to said cabinet in each of a plurality of vertical positions of said shelf.

5. In a machine support and cabinet assembly for business machines comprising a cabinet having a plurality of front walls including a re-entrant angular section, a platform for supporting a business machine, means supporting one side of said platform from the adjacent side of said cabinet, a supporting structure for supporting the other side of said platform, a shelf extending obliquely from said re-entrant angular section of said cabinet, means on a plurality of adjacent sides of said shelf and on a corresponding plurality of walls of said re-entrant angular section for rigidly and releasably attaching said shelf to said cabinet in each of a plurality of vertically disposed positions and a storage compartment in said cabinet to the rear of said shelf.

6. In a combined machine support and cabinet assembly for business machines including a cabinet, a device for supporting a business machine suspended on one side from the adjacent side of said cabinet and means for supporting the other side of said device, the combination of a recess in the front of said cabinet, a shelf having a portion of the circumference thereof shaped to conform to the shape of said cabinet recess, three or more attaching means on the circum-

ference of said shelf, at least one of said attaching means being spaced apart from a line drawn through others of said attaching means and means cooperable with said attaching means and at a plurality of vertically spaced positions on said cabinet for rigidly attaching said shelf in said recess at various vertical positions.

7. In a combined machine support and cabinet assembly for business machines including a cabinet, a device for supporting a business machine suspended on one side from the adjacent side of said cabinet and means for supporting the other side of said device, the combination of a shelf, an angular recess in the front of said cabinet, a portion of said shelf so formed as to enter into said recess in said cabinet, the remainder of said shelf extending in front of said cabinet at an oblique angle to the plane of the front of said cabinet, securing means on a plurality of sides of said shelf and means on a corresponding plurality of walls of said cabinet at vertically spaced positions and cooperative with said securing means for rigidly attaching said shelf to said cabinet in each of said vertically spaced positions.

8. In a combined machine support and cabinet assembly for business machines including a cabinet, a device for supporting a business machine suspended on one side from the adjacent side of said cabinet and means for supporting the other side of said device, the combination of a shelf, an angular recess in the front of said cabinet,

inet, a portion of said shelf so formed as to enter into said recess in said cabinet, the remainder of said shelf extending in front of said cabinet at an oblique angle to the plane of the front of said cabinet, securing means on a plurality of sides of said shelf, a compartment in the upper portion of said cabinet to the rear of said shelf and a second compartment in the lower portion of said cabinet below the first compartment and below the lowermost position of said shelf.
